UNITED STATES PATENT OFFICE.

WILLIAM S. ROBERTS, OF BOLIVAR, NEW YORK.

BARBED FENCE.

SPECIFICATION forming part of Letters Patent No. 276,883, dated May 1, 1883.

Application filed December 14, 1882. (No model.)

To all whom it may concern:

Be it known that I, WILLIAM S. ROBERTS, a citizen of the United States, residing at Bolivar, county of Allegany, State of New York, have invented certain new and useful Improvements in Barbed Fences, of which the following is a specification, reference being had therein to the accompanying drawings, which form a part of the same, and in which—

10 Figure 1 is a perspective view of my invention, and Figs. 2, 3, and 4 are detail views.

Similar letters of reference indicate corresponding parts in all the figures.

15 My invention has relation to that class of barbed fences in which a metallic strap is provided at intervals with sheet-metal barbs inserted through slits in the same; and it consists in the detailed construction and combination of parts of the same, as hereinafter 20 more fully described and claimed.

In the accompanying drawings, the letter A indicates a strap of metal, having at suitable intervals longitudinal slits b at an equal distance from both edges of the strip, through 25 which the barb-plates B are inserted. These plates are cut so as to form a rectangular central portion, a, of the same width as the length of the slits b, and slightly longer than the width of the strap, and are provided at their 30 upper and lower edges with sharp points c. The incisions d, which form the inner edges of these points, form two trapezoidal lips, f, between the points upon the upper and lower edge of the central portion, a, of the barb-plate. The barb-plates are fastened upon the 35 straps by inserting them through the slits in the same, which they fill up, whereupon they are bent at their middle, one half being bent upward and the other bent downward. The 40 lips f are then bent over the upper and lower

edge of the strap, clasping the same firmly, as shown in Fig. 2, and the barbs or points c bent to stand out horizontally from the edges of the strap, the barbs upon the same side of lips f being bent in opposite directions, as 45 shown in sectional view, Fig. 4, and in Fig. 1. In this manner it will be seen that the barbs are securely fastened to the strap, they being secured from sliding laterally upon the strap as well as from falling off if one or more of the 50 barbs should be broken off in the course of time, thus making a very durable fence-barb, while the simplicity of the construction of the barbed plates and the strap and their manner of attachment make it easy and inexpensive 55 to manufacture.

I am aware that barbed fences have been made in which lips projecting from barbed plates have been bent over wires, and also that slotted strips have been used with pointed 60 plates inserted horizontally through the slits and twisted on both sides of the same, and I do not claim any of these constructions, broadly; but

What I do claim, and desire to secure by 65 Letters Patent of the United States, is—

In a barbed fence, the combination of the metallic strap A, having longitudinal slots b, with the barbed plates B, having points or barbs c, and trapezoidal lips f, inserted through 70 slots b and bent over the edges of the strap, in the manner and for the purpose shown and set forth.

In testimony whereof I affix my signature, in presence of two witnesses, this 17th day of October, 1882. 75

WILLIAM S. ROBERTS.
